FRANK LEWIS MORGAN, OF WASHINGTON, DISTRICT OF COLUMBIA, ASSIGNOR TO UNDERWOOD TYPEWRITER COMPANY, OF NEW YORK, N. Y., A CORPORATION OF NEW JERSEY.

TYPE-WRITING MACHINE.

1,071,170.

Specification of Letters Patent. Patented Aug. 26, 1913.

Application filed October 9, 1911. Serial No. 653,475.

To all whom it may concern:

Be it known that I, FRANK L. MORGAN, a citizen of the United States, residing in the city of Washington, District of Columbia, have invented certain new and useful Improvements in Type-Writing Machines, of which the following is a specification.

My invention relates to typewriting machines, and in particular to machines having a vibrating ribbon mechanism and means for shifting the platen. It is specially designed to be used in connection with a bi-chrome ribbon shift.

In the Underwood front strike typewriter, a vibrator raises the ribbon in front of the platen at each stroke of the type-bars. The vibrator is controlled by a universal frame, actuated by heels on the type-bars, and in the present invention may be actuated thereby by either of two pins which reciprocate with a bracket, head or housing on the universal frame. These pins may be arranged on opposite sides of the vibrator, and may be adapted to selectively enter holes in it at different distances from the pivot of the vibrator, whereby owing to the different leverage, one pin will give the vibrator a greater throw than the other. When therefore, a striped ribbon is used, either the top or the bottom may be brought between the type and platen, so that by having the proper pin actuate the vibrator, either desired color may be used. Keys are provided for shifting the pins in the housing so that the ribbon color may be readily controlled by the operator. The pins which actuate the vibrator may move up and down in said housing with the platen shift rail, and so shift with the shifting vibrator which is pivoted on said platen shift rail.

One advantage of my invention is that the vibrator is positively moved with the platen shift mechanism, and that if the apparatus is clogged with dirt, it cannot assume any wrong position but will remain locked in whatever position it may be found.

Other features and advantages will hereinafter appear.

In the accompanying drawings, Figure 1 represents my invention applied to an Underwood typewriter, and shows so much of the typewriter as is essential to understand my invention. Fig. 2 is an enlarged view of the pins and part of the shifting mecha-

nism. Fig. 3 shows the parts in section with the platen rail raised. Fig. 4 shows the parts in section with the platen rail in its normal position.

A type-bar 1 is swung by a key, not shown, to cause upper and lower case type 2 to strike against a platen, not shown, through a ribbon 3. As said type-bar rises, a heel 4 on it strikes a bar 5 of a universal member 6 to control the escapement, not shown, and to actuate the vibrator 7 so as to raise the ribbon shield 8 and carry ribbon 3 between the type and the platen. The vibrator 7 is pivoted at 9 on an arm 10 of the platen shift rail 11, and an arm 12 of said vibrator extends upwardly between the walls 13 and 14 of an actuator for the ribbon, in the form of a housing 15 fast on the universal bar 6. The platen shift rail is arranged in the usual manner to raise the platen so that upper case type 2 will write on it. Said vibrator is actuated by means of pins 18 and 19 forming part of a frame 21, which pins extend through slots 20 in said housing or actuator, and vibrate forwardly and rearwardly with said housing. The pins 18 and 19 are arranged respectively to enter openings 16 and 17 in the extension 12 of the vibrator, and may be so arranged that one of said pins always engages with one of said openings. Said framing 21 also comprises a rod 27 riding in slots 28 in said housing, so that it is always held alined by said housing or actuator, and it also comprises a slide 22 riding in the opening formed by two plates 22^a, which plates move up and down with the platen shift rail 11. It will therefore be seen that the pin frame 21 shifts with the platen shift rail, so that when upper case type 2 write on the platen, the ribbon 3 will be vibrated to the proper point in front of said type. Said plates 22^a, however, are not fast on said shift rail but form an extension of a link 11^a, which extension lies along said shift rail, and is held thereon by a pin 23 extending through a slot in said link 11^a. Said link may be moved longitudinally along said shift rail by means of keys 24 through a shaft 25 and rock arm 26, said rock arm having a pin and slot connection with said link. From this it will be seen that when either of the keys 24 is depressed, the rock arm 25 will be swung by them so as to shift said frame 21 in the hous-

ing 15 by means of a pin 22^b fast in said frame, which pin rides in a slot 22^c, formed in the upper plate 22^a. Said slot 22^c is so formed as to permit the slide 22 to run easily between the plates 22^a as the universal frame vibrates it. It will be seen that whenever a key 24 is depressed so as to cause the pin 18 to enter the opening 16, the vibrator 7 will have its longer end swung through a comparatively long arc, and so raise the ribbon 3 till the lower edge 3^b thereof is at the printing point; while if pin 19 enters the opening 17, the free end of the vibrator swings through a much smaller arc, and so moves the carrier 8 only sufficiently to raise the upper edge 3^a of the ribbon to the printing point. The pins 18 and 19 are preferably tapered so as to easily enter the openings 16 and 17 if the extension 12 does not 25 precisely aline with them. The link 11 may be carried at its end on the platen shift rail 11, where it is slotted at 29 to receive a screw 30 entered in the support 31 of said shift rail. The pin and slot connection is arranged to give sufficient play to accommodate the movement of the platen shift rail 11.

Having thus described my invention, I claim:

1. In a typewriting machine, the combination with a universal frame, of a platen shift rail, a ribbon carrier, a vibrator moving said ribbon carrier and pivoted to the platen shift rail, an actuator in the form of a housing on the universal frame, a pin frame in said housing carrying pins to engage with said vibrator and actuate it, a member carried by the platen shift rail to move said pin frame with it, and a member for shifting said pin frame to cause either 40 of said pins to engage with the vibrator.
2. In a typewriting machine, the combination with a universal bar, of an actuator thereon, slots in the opposite walls of said actuator, a vibrator extending between said 45 walls, a pin extending through each slot, a platen shift rail on which said pins are slidably mounted, and a key for shifting said pins so as to cause them to selectively engage said vibrator.
3. In a typewriting machine, the combination with a universal bar, of an actuator thereon, slots in the opposite walls of said actuator, a vibrator extending between said 55 walls, a pin extending through each slot, a frame comprising a slide carrying said pins, a platen shift rail, guides on said platen shift rail in which said slide may reciprocate, and by which it may be shifted, and a key for shifting said slide by 60 said guide.
4. In a typewriting machine, the combination with a universal bar, of an actuator thereon, slots in the opposite sides of said actuator, a frame comprising a bar and two 65 pins extending through said slots so as to

be held alined thereby, a vibrator extending to said actuator, and a key for selectively causing said pins to engage said vibrator.

5. In a typewriting machine, the combination with a universal bar, of an actuator thereon, slots in the opposite sides of said actuator, a frame comprising a bar and two pins extending through said slots so as to be held alined thereby, a vibrator extending to said actuator, a platen shift rail, guides shiftable on said rail, and a slide on said frame vibrating in said guides and shiftable on said rail with them.

6. In a typewriting machine, the combination with a universal frame and a platen shift rail, of a ribbon carrier, a lever vibrating said ribbon carrier pivoted on the platen shift rail, an actuator on the universal frame, a second frame shiftable in said actuator, means for moving it with the platen shift rail, pins on said second frame adapted to engage with said lever, and means to shift said second frame in said actuator to determine which pin shall engage with said lever.

7. In a typewriter, the combination with ribbon vibrating means and a platen shift rail, of a slide on said rail, a universal frame, pins carried by said slide to connect said vibrating means with the universal frame, and a link moving along said platen shift rail to determine which of said pins shall engage with said vibrating means, and so determine the throw of said vibrating means and the color of the ribbon.

8. In a typewriting machine, the combination with a universal bar, of an actuator thereon, a ribbon vibrator extending into said actuator, a platen shift rail, guides on said shift rail, a slide movable relatively to said actuator in said guides, and pins on said slide arranged to selectively engage said vibrator.

9. In a typewriting machine, the combination with a universal bar, of an actuator thereon formed with slots in its opposite walls, a vibrator extending between said walls, a pin extending through each slot, a slide carrying said pins, and a key for shifting said slide and pins so as to cause the pins to selectively engage said vibrator.

10. In a typewriting machine, the combination with a universal bar, of an actuator thereon formed with slots in its opposite walls, a vibrator extending between said walls, a pin extending through each slot, a frame comprising a slide carrying said pins, guides in which said slide may reciprocate, and by which it may be shifted, and a key for shifting said slide by said guide.

11. In a typewriting machine, the combination with a universal frame moved by the type bars, of a ribbon carrier, a vibrator for actuating the carrier, a platen shift rail, a fulcrum on said shift rail for said vibrator,

bearings in said vibrator at various distances from said fulcrum, an actuator on the universal frame, pins vibrated with said actuator adapted to bear in said vibrator, 5 a slide on the shift rail on which said pins move, and a link to shift said pins to cause either to enter a bearing on the vibrator to actuate it.

12. In a typewriting machine, the combination with a universal bar, of an actuator

thereon, a ribbon vibrator extending to said actuator, guides stationary with reference to said actuator, a slide movable in said guides by said actuator, and pins on said slide arranged to selectively engage said vibratory. 15
